(57) **CLAIM**

The ornamental design for a holder for a battery-powered tool, as shown and described.

DESCRIPTION

FIG. 1 is a front view of a holder for a battery-powered tool showing my new design.

FIG. 2 is a back view thereof.

FIG. 3 is a top view thereof.

FIG. 4 is a bottom view thereof.

FIG. 5 is a right side view thereof.

FIG. 6 is a left side view thereof.

FIG. 7 is right upper perspective view thereof.

FIG. 8 is left upper perspective view thereof

FIG. 9 is right lower perspective view thereof.

FIG. 10 is left lower perspective view thereof.

FIG. 11 is a front view of the holder for a battery-powered tool holding a battery-powered tool in a generally vertical, inverted orientation thereof.

FIG. 12 is a front view of the holder for a battery-powered tool holding a battery-powered tool in a generally horizontal orientation thereof.

FIG. 13 is a side view of the holder for a battery-powered tool holding a battery-powered tool thereof; and,

FIG. 14 is an upper perspective view of the holder for a battery-powered tool thereof.

The broken lines in the drawings illustrate portions of the holder for a battery-powered tool which form no part of the claimed design. The broken line portions shown in FIGS. 11 through 13 illustrate environmental subject matter only and form no part of the claimed design.

1 Claim, 8 Drawing Sheets
